UNITED STATES PATENT OFFICE.

ARTHUR HAMMERSTEIN, OF NEW YORK, N. Y.

TIME-CONTROLLED APPARATUS.

949,764.

Specification of Letters Patent. Patented Feb. 22, 1910.

Application filed February 20, 1908. Serial No. 416,859.

To all whom it may concern:

Be it known that I, ARTHUR HAMMERSTEIN, a citizen of the United States, and resident of the borough of Manhattan, city, 5 county, and State of New York, have invented certain new and useful Improvements in Time-Controlled Apparatus, of which the following is a specification.

My invention relates to time controlled 10 apparatus and has for its object to provide a mechanism which after a predetermined period of time will perform certain functions, such as for instance raising a carrier with eggs from the boiling water, or 15 operating an alarm to give notice of the fact that the period of time for which the apparatus was set has elapsed.

My invention will be fully described hereinafter and the features of novelty will be 20 pointed out in the appended claims.

In the accompanying drawings in which I have illustrated two forms of my invention; Figure 1 is a sectional elevation showing my apparatus in use, Fig. 1^a is an enlarged detail view of the piston rod; Fig. 2 is a front elevation of my device; Fig. 3 is an enlarged detail section of the air inlet valve; Fig. 4 is a front elevation of a different form of my apparatus and Fig. 5 is a 30 side elevation thereof.

The apparatus comprises a cylinder A to which is secured a bracket B having arms C and resilient tongues D. The bracket is further provided with a member E adapted 35 for engagement with the edge of a receptacle F, which receptacle is also engaged by the arms C, and the resilient tongues D which serve to hold the apparatus in operative position.

40 A piston G is arranged to work in the cylinder A, and is secured to a piston rod G' having an operating knob or handle G². The said piston G fits loosely in the cylinder so that air may pass slowly between it and the cylinder wall for the purpose to be more 45 fully described hereinafter. A groove G³ extends longitudinally of the piston rod G' and co-operates with a projection G⁴ located on the inside of the cylinder head, to prevent the said piston rod from turning. A 50 coil spring II is located inside of said cylinder between the piston G and the cylinder head A'. The lower cylinder head A² is provided with an air inlet having a valve seat I' and a valve I secured to a stem I², which valve is maintained in its normal or

closed position by a spring I³. The piston rod G' passes between two members of a lever J pivoted at J' upon the cylinder head A' and having an inclined slot J² near its free end. A link K is provided with a pin K' arranged to work in said slot J² and is pivotally connected at K² with a latch L fulcrumed at L' on the cylinder A. This link K also carries a member K³ which serves as an indicator in connection with a scale G⁵ which is produced on the piston rod G' to indicate the period of time which will elapse before the apparatus will perform the function for which it is intended. This member K³ also acts as a retaining device in connection with grooves G⁶ extending around the piston rod at the various points of the scale, to hold said piston rod as will be hereinafter described. A supporting hook 75 M pivoted at M' to an upward extension of the bracket B is thrown into its upper or inoperative position by a spring M². The hook M is connected by means of a link N' with a piston N of a dash-pot N² secured 80 to said bracket B. The said hook is also provided with a nose M³ adapted for engagement with the latch L as will be more clearly brought out hereinafter.

O is a carrier, in the present instance a circular plate having openings O' for the reception of eggs O². A handle or rod P is secured to the central portion of the said carrier and is provided with spaced projections P' and an eye P² arranged for engagement with the free end of the hook M. 85

Assuming the device is in position on a receptacle and is intended for timing the boiling of eggs the operation is as follows: The piston rod G' is drawn outward until 95 the desired number of the scale G⁵ registers with the member K³, which member is then moved into the circular groove G⁶ at this point and maintains the piston in its outward position (Fig. 1^a). For instance the 100 scale may indicate minutes so that if the piston rod is drawn out until the number IV registers with the member K³, it would indicate that four minutes would elapse before the apparatus would perform its function. 105 In thus drawing out the piston rod the suction induced by the piston opens the valve I and permits air to enter the cylinder at this point. After the piston rod G' has been drawn out the required distance, the carrier 110 in the present illustration with eggs therein is then placed upon the hook M, and the

latch L is engaged with the nose M³ of the hook M, which has been swung on its pivot to permit this thus submerging the eggs in the boiling water. As the nose M³ is engaged with the latch L, the lever K having some free motion, will move the forked member K² from engagement with the circular grooves G⁶ and release the piston rod G' the moment the eggs reach the boiling water (Fig. 1). The spring H now begins to force the piston G downward. The action of the spring is retarded by the air which is between the piston G and the cylinder head A² which air passes slowly by the piston G owing to the fact that the said piston fits the cylinder loosely, the valve I being kept closed meanwhile owing to the pressure of the air thereon. The piston slowly descends until the head G² of the piston rod engages the lever J which is now forced downwardly causing the pin K' of the lever K to ride up in the slot J². As soon as the said pin K' has reached the upper portion of said slot, which takes place before the piston has reached its lowermost position, the continued pressure of the head G² forces the lever J to further descend and thus moves the link K in a downward direction, thus causing the latch L to swing on its pivot L'. As soon as the latch L has moved down enough to release the nose M³ of the hook, the said hook is forced upward to its normal position by the spring M² and swings the carrier with the eggs thereon out of the boiling water. This upward movement of the hook is retarded by the dash pot N² and piston N so that the motion is a slow and gradual one and doing away with the danger of breakage or other injury to the contents of the carrier. The eggs are then removed from the carrier and the operation repeated. It will thus be seen that my apparatus is simple and highly effective and is adjustable to different lengths of time, by simply drawing the piston rod out more or less as desired. Furthermore the timing begins at the instant desired, in the present case, the moment the eggs reach the boiling water.

In many instances it may be desirable to sound an alarm upon the lapse of a predetermined length of time, in which case the device illustrated in Figs. 4 and 5 may be used. In this form of my invention the cylinder a is provided with a bracket b secured thereto by collars b' and screws b² for hanging or otherwise supporting the device. c is a bell which is suitably mounted on the cylinder a and provided with the usual spring capable of being wound and which when unwinding as hereinafter described operates the clappers or hammers d to sound the bell. A pinion e is secured to the shaft e' of the bell, to which one end of the spring is also fastened. The other end of the spring is secured to the customary stationary point.

A bar e² is loosely mounted on the shaft e' of the bell and carries a spring pressed pawl e³ which engages the teeth of a ratchet wheel e⁴ secured to the shaft e' to turn therewith. The pinion e meshes with a rack f capable of sliding in guides h carried by the cylinder a. The upper end of this rack is bent and is provided with an opening f' into which extends a projection g³ located on the head g² of the piston rod g⁵. This piston rod g⁵ passes through an eye located in the member i' of the arm i which arm is pivoted at i² between lugs i³ fastened to the cylinder a. This arm i is also provided with another member i⁴ having a nose i⁵ for holding the clapper against movement through its engagement with the pin e⁵ on said bar e². A spring i⁶ tends to maintain the said arm in its normal position. In other respects this form of my device is the same as shown and described with regard to Figs. 1, 2, and 3. This form of my invention operates as follows: The piston rod is drawn out in the same manner as hereinbefore described, until the scale thereon indicates the length of time it is desired to have elapse until the alarm is sounded. This drawing out of the piston causes the rack f to move with it and to rotate the pinion e to wind up the bell spring. During this winding of the spring, the pawl e³ simply rides over the teeth of the ratchet e⁴ so that the bar e² is stationary while the spring is wound. After the piston rod has been drawn out the required distance, it is released and immediately begins to return to the cylinder in the same manner as described in regard to Figs. 1, 2, and 3. As the piston and piston rod return to the cylinder the projection g³ is withdrawn from the opening f' of the rack f, thus leaving the said rack in its outer position. As soon as the head g² engages the arm i and swings said arm on its pivot i² the nose i⁵ is withdrawn from engagement with the pin e⁵ of the bar e² and permits the spring to unwind and to operate the hammer which also causes the rack f to return to its initial position. The user is thus informed that the predetermined period of time has passed.

It is to be understood that any bell mechanism suitable for the purpose may be used in place of the one I have shown and described.

I claim—

1. In a time controlled apparatus, the combination of a cylinder; a piston arranged to move therein by gradually displacing the contents of the cylinder; a graduated rod on the piston; a device for engaging the rod to hold it temporarily in its set position; a trip lever carried by the cylinder; and means for tripping said lever controlled by the movement of the piston.
2. In a time controlled apparatus, the com-

- bination of a cylinder; a piston arranged to move therein by gradually displacing the contents of the cylinder; a graduated rod on the piston; a device for engaging the rod 5 to hold it temporarily in its set position; a trip lever carried by the cylinder; means for tripping said lever controlled by the movement of the piston; and means associated with said lever for tilting it upward when 10 it is released.
3. A time controlled mechanism comprising a cylinder, a piston movable therein, a hook pivotally carried by said cylinder, a carrier supported by said hook, a latch for 15 maintaining said hook in its operative posi-
- tion, means secured to said piston for releasing said latch to permit said hook to return to its initial position, after a predetermined period of time has elapsed, and means connected with said hook for regulating the 20 movement of said hook as it returns to its initial position.

In testimony whereof I have signed my name to this specification in the presence of two subscribing witnesses.

ARTHUR HAMMERSTEIN.
